METHOD AND APPARATUS FOR SMOOTH-
FINISH GEAR GRINDINGEdward W. Miller, Springfield, Vt., assignor to
The Fellows Gear Shaper Company, Springfield,
Vt., a corporation of Vermont

Application May 14, 1942, Serial No. 442,884

4 Claims. (Cl. 51—123)

This invention relates to the art of gear grinding; i. e., that of grinding the teeth of hardened gears to generate involute face curves with the highest obtainable accuracy of dimensions and form. Its object is to give to the work a smoother, and generally more desirable quality of surface finish than is obtainable by the grinding instruments and procedures heretofore used, and at the same time to make the finished teeth at least as accurate as the best results of prior practices.

Generative gear tooth grinding is accomplished by producing a relative rolling movement between the gear being ground and a grinding wheel, similar to that between a gear and a rack running in mesh, while the wheel is rapidly rotated at efficient cutting speed. In many cases a relative displacement is effected between the gear and grinding wheel in the direction of the axis of the gear to distribute the grinding effect uniformly throughout the length of the teeth. Usually both components of rolling motion (translative displacement and rotation) are imparted to the gear, but in some instances the gear is rotated only while the grinding wheel is displaced tangentially of, and at the same linear speed as, a pitch circle of the gear with respect to which the rolling movement is established.

Heretofore two different types of grinding wheels have been generally employed for performing this class of work. One type of wheel is provided with a flat grinding face occupying a plane perpendicular to its axis of rotation and is set with its active face at an oblique angle to the direction of the translative component of the relative rolling motion, such that the portion of its surface nearest to the gear coincides with the face of a rack tooth conjugate to the gear. The other type of wheel is provided with convex conical faces at opposite sides of its circumference, the elements of which include between them an angle equal to that between the opposite side faces of such a conjugate rack tooth giving it the form, in profile, of such rack tooth; and it is mounted to rotate in a plane perpendicular to the direction of the translative component of rolling movement. While both of these types of wheel are capable of generating accurate tooth faces and produce results which are entirely satisfactory for many purposes, yet the flat-faced wheel tends to become loaded with the material removed from the work and to become over-heated, and the rack-shaped wheel does not produce as fine a quality of finish as

is desirable for other purposes. It is for the purpose of rapidly generating gear tooth faces with a satisfactorily smooth finish, and without over-heating, that the present invention has been devised.

The invention consists in the combination of a grinding wheel having a conical active face, of which the elements are inclined to the plane of rotation at a distinct angle which is less than the pressure angle of the gear to be ground, with other machine elements, organized to support and rotate the wheel in a plane which is neither perpendicular to the translative component of motion between wheel and work gear, nor perpendicular to the line of rolling action, but is at an intermediate angle such that the active face elements of the wheel, when in tangent contact with a tooth face of the work, coincide with the tooth face of an imaginary rack conjugate to the gear. It further consists in a method or procedure by which such a wheel is caused to operate on a work piece in the manner set forth. The characteristics and particulars of this invention will now be further explained in connection with illustrative drawings.

In the drawings,

Fig. 1 is an elevation, partly in section, of part of a gear grinding machine embodying the novel grinding wheel of this invention and provisions for effecting operative coaction between the grinding wheel and a gear being ground;

Fig. 2 is a fragmentary side elevation of the machine showing the work gear and grinding wheel, with part of the means for supporting them, in the same cooperative relation as in Fig. 1;

Fig. 3 is a diametral sectional view, on a larger scale, of the upper half of the grinding wheel shown in Figs. 1 and 2 in its cooperative relation with one of the teeth of a work gear;

Fig. 4 is a side view of one of the gear teeth finished by the means of the present invention, showing in a diagrammatic way a comparison of the surface finish produced by this grinding wheel and the finish produced by grinding wheels of the prior art;

Fig. 5 is a fragmentary sectional view taken on line 5—5 of Fig. 3, and drawn on a smaller scale, to illustrate the character of contact between the grinding wheel of this invention and the work;

Fig. 6 is a view similar to Fig. 3 showing a plane faced grinding wheel of the prior art and its cooperative relation to the work in performing its grinding action;

Fig. 7 is a view similar to Fig. 4 showing in a diagrammatic, comparative way the type of surface finish produced by plane faced wheels on gear teeth;

Fig. 8 is a fragmentary sectional view taken on line 8-8 of Fig. 6 showing the character of contact between the plane faced wheel and the work;

A typical grinding machine is illustrated in Figs. 1 and 2 having means for simultaneously displacing laterally, and rotating about its axis, a work gear G so that in effect a pitch circle pc of the gear rolls without slip on a straight pitch line pl . Many types and forms of means for effecting such rolling movement are available in the art, and I have chosen as typically illustrative the machine disclosed in my Patent No. 2,364,542, granted December 5, 1944, on an application Serial No. 438,136, filed April 8, 1942. The work gear is mounted on a spindle 1, rotatable for indexing purposes in a carrier 2, to which are fixed cams or formers 3 entering between and supported by inclined abutments 4 and 5. The contact faces of the former 3 and the abutments 4 and 5 are suitably correlated to cause translative movement of the carrier and spindle to right or left according as the carrier is turned in clockwise or counterclockwise rotation, respectively, at a rate which effects the desired non-slip rolling of the pitch circle pc on the pitch line pl . The movement of the gear then is the same as though it were rolled, on a stationary conjugate rack, such as the rack R shown in broken lines in Fig. 3.

The grinding wheel W is secured to a spindle, not shown, rotatably mounted in a holder 6 and driven at suitable speed by a motor 7. The projection on the plane of the drawing of the axis of rotation is designated by the line $a-a$ and it is arranged transversely to the axis of the work gear and at a suitable distance therefrom to enable one edge of the grinding wheel to cross the pitch line pl and enter between two teeth of the gear. The wheel holder 6 is coupled by a pivot 8 with a base 9 so that the inclination of the axis $a-a$ to the pitch line pl can be varied and adjusted. Base 9 is in turn adjustably mounted on a sub base 11 and the latter is secured to a bed 12 which is reciprocable lengthwise of the work spindle axis and is so reciprocated by means fully shown in said Patent No. 2,364,542 and made a part hereof, to transport the grinding wheel from end to end of the tooth being ground in order that the grinding effect may be equally distributed over the face of the gear.

The grinding wheel of this invention differs from the grinding wheels of the prior art in that its active part is a convex conical zone c contiguous to the circumference, the radial elements of which make an angle m with the plane of rotation of the wheel (here typified by the surface p perpendicular to the axis $a-a$) which is smaller than the pressure angle of the work gear. The pressure angle is the angle pa between the pitch line on which the gear meshes with its conjugate base rack, indicated by pl in Figs. 1 and 3, and the line of action, indicated by the line la in Fig. 3. The tooth faces of the base rack are perpendicular to the line of action.

The plane faced prior art grinding wheels, of which an example is shown at W' in Fig. 6, have an active face c' contiguous to the circumference lying in a plane perpendicular to the axis of rotation, and the wheel is mounted for oper-

ation with this plane perpendicular to the line of action la and the part of the zone c' contiguous to the tooth being ground coinciding with the face of a tooth of the imaginary base rack. The axis $a'-a'$ of this wheel then is parallel to the line of action. In Fig. 6 the lines $f-g$ and $f-h$ are respectively parallel and perpendicular to the pitch line on which the relative rolling motion takes place between the work and the wheel W' , and the angle between the axis $a'-a'$ and the line $f-g$, as well as that between the plane of the active zone c' and the line $f-h$ is equal to the pressure angle pa .

The other type of prior art wheel previously mentioned, is formed with convex conical active faces, adjacent to the circumference, at opposite sides of its median plane, the radial elements of such conical faces make angles with the median plane equal to the pressure angle; wherefore the profile of the wheel at the rim is similar in outline to a tooth of the base rack. The conical faces are intended and adapted to generate the respectively opposite faces of two gear teeth; and the wheel is set up for operation with its axis parallel, and its median plane perpendicular, to the pitch line of the relative rolling movement.

By contrast to the operative organization of the prior art tools, the wheel W of this invention is set for operation with its axis $a-a$ making an angle n , equal to the difference between the pressure angle pa and angle m , with the line $k-l$ parallel to the pitch line of rolling movement. Its value is such that the element of the active zone c momentarily in central tangent contact with the work is perpendicular to the line of action and coincides with a tooth face of the imaginary base rack.

For purposes of comparison, the wheels W and W' have been shown in these drawings in their proper relationship with the same work gear and base rack, having a pressure angle of 14° . Wheels made and used in accordance with this invention may be designed for grinding gears of any pressure angle; but, whatever the specific proportions and dimensions of any given wheel may be, the same characteristic differences exist between it and the wheels of plane faced and rack profile type.

Experience has demonstrated that grinding wheels embodying the characteristics of this invention produce smoother surfaces and a better quality of finish than wheels of the rack profile type made of the same grade and quality of abrasive grains and operated under like conditions. Wheels of the plane faced type produce a mottled finish made up of curved lines due to the fact that the wheel makes continuous contact with the work throughout so much of the length of the tooth as is overlapped by the wheel face. When the wheel is moved lengthwise of the gear, or vice versa, in grinding wide faced gears, the curved lines cross each other. The nature of these crossing curved lines is shown diagrammatically in Fig. 7, which represents one side of the work gear tooth t , shown in Fig. 6, after having been ground with the wheel W . They are finer, more numerous, and more closely spaced than as indicated in the diagram, and are always present in gears so ground. The contact between the gear tooth lengthwise thereof and wheel is shown in Fig. 8, which is a fragmentary section on a plane coinciding with the line of action.

In the case of the rack type wheel, contact is

made with the work at the mid point of a curve which approximates closely the arc of a circle of which the radius is equal to the length of the line of action from the point of contact to its intersection with the wheel axis. This radius is a maximum at the circumference of the wheel and is shorter at points inward from the circumference. Essentially point contact occurs with the work. Owing to this narrow contact, and the fact that the wheel must be traversed back and forth along the gear tooth face, the surface finish is composed of parallel lines. This type of finish is desirable. However, a still greater refinement of finish is more desirable in some instances.

The finish accomplished by the present invention is composed of straight lines, which are finer, shallower, more closely spaced, and more uniform than those cut by the rack type wheel, and they are free of the mottled roughness characteristic of the results obtained by the plane faced wheel. The improved results are believed to be due to the fact that the angle between the axis $a-a$ of the wheel and the line of action is less, and may be much less, than that of the rack type wheel, while at the same time it is a definite angle of positive value. Thus the active face of the wheel in the plane of action is a curve, but its radius at the contact point with the work is substantially longer than that of the rack type wheel, and may be several or many times as long. Thus a wider contact is obtained between the wheel and the work. Although, in geometrical concept, the contact between a curve of any radius, however large, and a straight line is always a point, yet where similar relations occur between material articles, the properties of the materials and other conditions cause modifications, wherefore actually there is an extended contact between the large radius curve of the cutting zone c and the work gear tooth.

Cutting action occurs simultaneously at both sides of the mid tangent point r' to a greater extent than in the case of the rack type wheel, and this contributes to the greater uniformity and smoothness of finish.

At the same time, the length of contact is limited, as compared with the long area of contact of the plane faced wheel, gradually fading out at each side of the center of contact r' . Hence the new wheel has a freer cutting action than the plane faced wheel, giving better opportunity for escape of chips and avoiding the clogging, impairment of cutting action and over-heating which occurs with such extended contact.

Any desired value may be given to the cone angle m of my improved grinding wheel, provided it is smaller than the pressure angle but has a positive value. Excellent results have been obtained with an angle of 1° , and also with larger angles. While the exact value of the angle is not critical, the fact that a contact curve of definite radius, substantially larger than the radius of the rack type wheel, may be obtained, is critical.

The principles of the invention are not limited to the particulars of means for effecting relative rolling traverse between the gear and the grinding wheel. Any means available for that purpose may be used, whether operating to impart both components to the work, or the angular component to the work and the linear displacement to the wheel, provided only that the correct ratio between these components is maintained to effect non-slip rolling action between a prescribed pitch curve of the work piece and a straight tangent

pitch line. It is essential that the wheel be supported with its rotational plane parallel to the length dimension of the work gear teeth, whether the gear is a spur or a helical gear. For operating on spur gears, such rotational plane is parallel to the axis of the gear, while in connection with helical gears it is disposed at an inclination to the gear axis equal to the helix angle of the gear. It is further practically important that the wheel be mounted with provision for angular adjustment of its axis so that the contact element of the wheel may be brought into coincidence with a tooth face of the imaginary conjugate rack in meshing relation with the work gear. By means of such adjustment a grinding wheel having its active face disposed at any angle to the rotational plane may be brought to the correct relation with a work gear of any pressure angle.

What I claim and desire to secure by Letters Patent is:

1. Apparatus for generatively grinding gears comprising a rotatably mounted grinding wheel having a convex conical grinding face contiguous to its circumference, of which the angle between its radial elements and the plane of rotation is substantially smaller than the pressure angle of the gear being ground, means for effecting a relative rolling movement between the work gear and said grinding wheel on a pitch line inclined to the axis of the wheel at an angle equal to the difference between the pressure angle and the before named angle, and means for effecting a relative translative displacement between said gear and wheel lengthwise of the gear teeth so as to generate the same face curvature throughout the length of said teeth.
2. A generative gear grinding machine comprising a grinding wheel, means supporting said wheel rotatably, means for rotating the wheel, a work holder, means for effecting relative movements of rotation and translation between said work holder and grinding wheel such that a gear secured to the work holder is caused in effect to roll in non-slip pitch circle engagement with a pitch line intersecting the rim of the grinding wheel, the wheel having a lateral convex conical grinding face adjacent to its circumference, of which the cone angle with the plane of rotation is substantially less than the pressure angle of the gear to be ground, means for effecting relative translative displacement between the wheel and gear lengthwise of the gear teeth, and means for angularly adjusting the wheel supporting means to bring the axis of the wheel at an angle to said pitch line equal to the difference between the said pressure angle and said cone angle.
3. A machine for generatively grinding gear teeth comprising a supporting structure, a work support including a spindle adapted to carry a work gear and a grinding wheel support both mounted on the supporting structure, means for effecting relative movements between said work support and grinding wheel support compounded of rotation of the spindle and relative displacement in a straight path transverse to said spindle, a grinding wheel mounted rotatably on said supporting structure in position to act upon the tooth face of a gear mounted on the spindle, said wheel having a convex conical active face contiguous to the circumference, of which the cone angle with respect to the plane of rotation is substantially smaller than the pressure angle of the gear, and the wheel being located with the portion of its active face nearest to the gear extending across the path of relative translation at an angle to such

path which is the complement of the said pressure angle, and means for effecting relative displacement between the work holder and grinding wheel in the general direction of the axis of the gear to distribute the grinding action lengthwise of the gear teeth.

4. The method of generatively grinding the tooth faces of a gear to a pressure angle of greater than 0° , which consists in effecting relative rolling movement between such gear and a grinding wheel such that a pitch circle of the gear, other than its base circle, in effect rolls without slip on a straight pitch line, such a grinding wheel

having a conical active face adjacent to its periphery, of which the cone angle with respect to its plane of rotation is greater than 0° and substantially less than said pressure angle, and being located so that the rim of the wheel crosses said pitch line and the plane of rotation of the wheel is inclined to such line at an angle less than the pressure angle, rotating the wheel in said plane while the relative rolling movement takes place, and relatively displacing the gear and wheel lengthwise of the axis of the wheel.

EDWARD W. MILLER.
